UNITED STATES PATENT OFFICE.

JOHANN FECHTIG, OF WYHLEN, GERMANY.

SHED FOR AERIAL VESSELS.

968,336.

Specification of Letters Patent. Patented Aug. 23, 1910.

Application filed October 7, 1909. Serial No. 521,571.

To all whom it may concern:

Be it known that I, JOHANN FECHTIG, a subject of the German Emperor, and resident of Wyhlen, in the Grand Duchy of Baden and Empire of Germany, have invented certain new and useful Improvements in Sheds for Aerial Vessels, of which the following is a specification.

My invention relates to sheds for aerial vessels and particularly for dirigible balloons, and has for its object to enable such vessels to be readily housed or despatched, whichever the direction of their travel may be. For this purpose I have combined a turntable with a plurality of individual sheds disposed radially, as will be fully described hereinafter, the novel features of my invention being pointed out particularly in the appended claims.

Reference is to be had to the accompanying drawings, in which—

Figure 1 is a vertical section on line 1—1 of Fig. 2; Fig. 2 is a plan view of a balloon shed embodying my invention.

A plurality of stationary individual sheds A of any suitable construction are so arranged as to converge toward a central space, that is to say, the sheds A radiate from a common center. However they terminate at a distance from the center, so as to leave at their inner ends, a space the diameter of which exceeds the length of the largest balloon to be accommodated. The sheds are provided at their inner and at their outer ends with openings adapted to be closed by suitable doors as indicated at B, and are of proper dimensions to receive and protect balloons, such as the balloon C. Between the inner ends of the stationary sheds

A is arranged a turntable D mounted to revolve horizontally and provided with suitable means for connecting it temporarily with a balloon. As shown in the drawings my invention comprises a movable shed E carried by the turntable D so as to turn therewith and of substantially the same construction as the stationary sheds A, and this movable shed may also have doors F at its ends. The turntable D may be mounted on circular tracks G.

Upon the approach of an airship desiring to enter the building, the movable shed E will be brought to face in the direction of

the prevailing wind, and the balloon will be received therein and then transferred to one of the stationary sheds A by a proper operation of the turntable, which enables the movable shed to be alined with any one of the stationary sheds. The doors B, F will be opened and closed at the proper times to admit and securely house the airships. Of course, if the wind should happen to blow in the direction in which one of the empty stationary sheds faces, it will not be necessary to receive the balloon in the movable shed E, but it may be run directly into such stationary shed. The departure of a balloon will take place in a similar way. That is to say, the balloon will be brought out from its stationary shed A either directly (if the wind blows in the longitudinal axis of said shed), or after first transferring it to the movable shed E and turning the latter until it is in line with the direction of the wind.

Various modifications may be made without departing from the nature of my invention as defined in the claims.

I claim as my invention—

1. The combination of converging stationary sheds for aerial vessels, a turntable arranged adjacent to said sheds, and a shed carried by said turntable to turn therewith and adapted for alinement with any one of the stationary sheds.

2. The combination of a turntable, a balloon shed carried thereby to turn therewith, and a plurality of stationary sheds radiating from the center of the turntable and extending outward from the periphery of said turntable, said stationary sheds being adapted for alinement with the movable shed.

3. The combination of a stationary shed for aerial vessels, a turntable arranged adjacent to said shed, and a shed carried by said turntable and adapted to be brought into and out of alinement with the stationary shed.

In testimony whereof I have hereunto affixed my signature in the presence of two subscribing witnesses.

JOHANN FECHTIG.
